UNITED STATES PATENT OFFICE.

CHARLES CART, OF LE LOCLE, SWITZERLAND, ASSIGNOR TO SUSSFELD, LORSCH & SCHIMMEL, A PARTNERSHIP CONSISTING OF HENRY LORSCH, EDWIN S. LORSCH, AND S. SCHIMMEL, ALL OF NEW YORK, N. Y., AND HUGO SUSSFELD, JULES SUSSFELD, AND EDMUND SUSSFELD, ALL OF PARIS, FRANCE, DOING BUSINESS AT NEW YORK, N. Y.

SUPPORT INTENDED FOR HOLDING CLOCKWORK MOVEMENTS WHEN BEING MOUNTED.

Application filed June 21, 1924, Serial No. 721,604, and in Switzerland July 21, 1923.

This invention relates to an improved support for holding clockwork movements during mounting.

An object of this invention is to hold the 5 pallet plate of the clockwork movement when being mounted by the so called "hand mounting."

A further object of this invention is to provide an adjustable gripping device 10 wherein gripping jaws are displaceable into different positions parallel one to the other.

A further object of the invention is to form a device which is simple in construction and easy to manipulate.

15 One form of construction of the invention is shown as an example in the accompanying drawings, in which:—

Figure 1 is a view in elevation, and

Figure 2 is a plan view.

20 The jaws 1 and 2 of the support intended for holding the clock work movements in position when they are being mounted, are connected by a pair of links 3 and 3' pivotally connected to the jaw 1 and to similar 25 links 4 and 4' in turn pivotally mounted on the jaw 2.

The jaw 1 is provided with a rod 5 sliding in a sleeve 6 fixed to the jaw 2. A spring 7 is arranged about the rod 5 and the 30 sleeve 6 said sleeve having one of its ends fixed to the jaw 1 and the other to the jaw 2.

This spring 7 is a tension spring and tends to bring the jaws 1 and 2 together.

Claws 8, 8' are arranged on the jaw 1 and claws 9, 9' on the jaw 2 and are adapted 35 to hold between them the pallet plate of a clockwork mechanism so that said plate is embedded therein and the clockwork movement thus be held in position.

I declare that what I claim is:—

40 1. Apparatus for holding clockwork mechanism in position when being mounted, comprising a pair of jaws, telescopic connecting means between said jaws, a tension spring concentric with said connecting means connected to each of said jaws and tending to draw the same together, and toggle links connecting said jaws.

45 2. Apparatus for holding clockwork mechanism in position when being mounted, comprising a pair of jaws, telescopic connecting means between said jaws, a tension spring concentric with said connecting means connected to each of said jaws and tending to draw the same together, and toggle links 50 connecting said jaws, claws mounted on said jaws and adapted to hold the pallet plate of a clockwork mechanism.

55 In witness whereof, I have hereunto signed my name.

CHARLES CART.
